UNITED STATES PATENT OFFICE.

WALLACE L. SEVERANCE, HENRY J. JOHNSON, AND SAMUEL P. WALLACE, OF FREEPORT, ILLINOIS, ASSIGNEES OF ONE-FIFTH TO ALBERT STOLLER, OF FREEPORT, ILLINOIS.

CARBURETER.

SPECIFICATION forming part of Letters Patent No. 783,648, dated February 28, 1905.

Application filed August 22, 1904. Serial No. 221,758.

To all whom it may concern:

Be it known that we, WALLACE L. SEVERANCE, HENRY J. JOHNSON, and SAMUEL P. WALLACE, citizens of the United States, residing at Freeport, in the county of Stephenson and State of Illinois, have invented a new and useful Carbureter, of which the following is a specification.

This invention relates to devices of that class employed for carbureting air or gas to be used for lighting or power.

The principal object of the invention is to provide a carbureter of very simple and economical construction and one in which the level of gasolene or other hydrocarbon will be constantly maintained, so as to insure uniformity of saturation of the air or gas.

A further object of the invention is to provide a novel form of absorbent-carrier, so that an extensive surface of saturated textile material will be presented for contact with the air during its passage through the carbureting-chamber.

With these and other objects in view, as will more fully hereinafter appear, the invention consists of the novel construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a plan view of a carbureter constructed in accordance with the invention, the cover-plate being removed. Fig. 2 is a transverse sectional view of the same on the line 2-2 of Fig.

Fig. 3 is a detail perspective view on the line 3-3 of Fig. 2, illustrating more particularly the arrangement of the float-chamber. Fig. 4 is a detail perspective view of a portion of one of the absorbent-carriers.

Similar numerals of reference are employed to indicate corresponding parts throughout the several figures of the drawings.

The carbureting-chamber is in the form of

a shallow and preferably rectangular tank 1, formed of galvanized iron or other sheet metal, and within the tank are arranged a series of vertically-disposed partitions 2, also formed of sheet metal. The partitions 2 extend from top to bottom of the tank and are arranged in staggered relation—that is to say, they project alternately from opposite sides of the casing—and form a tortuous passage for the flow of the air. At one corner of the tank is an inlet-compartment 3, into which the gasolene or other liquid hydrocarbon is admitted through a pipe 4, and said pipe has a valve 5, that is controlled by a float 6, arranged within the chamber 3 and serving to automatically open and close the pipe 4, and thus maintain a constant level of liquid in the chamber and throughout the whole of the tank. This compartment is arranged immediately beneath a transparent panel 7, held in the frame 8, which is bolted to the top of the tank, the panel permitting constant inspection of the float, so that any derangement of the mechanism may at once be detected. One of the partitions 2 is shorter than the remaining partitions and extends from the end of the compartment 3 to a point near the opposite side of the casing, and that end of the partition adjacent to the compartment 3 is supported by a pair of cross-bars 9, so arranged as not to interfere with the flow of liquid or air, both of which are free to pass from the entrance of the compartment into the two panels separated by the short partition 2'.

In each of the panels formed between the two adjacent partitions 2 are a number of parallel frames 10, which serve as supports for the absorbent material 11, formed of wicking or other suitable material, which will absorb the hydrocarbon and carry it up above the level of the liquid in the carbureting-chamber. The absorbent material does not extend for the full length of the frames 10, so that at both ends of said frames are clear passages for the air and the air is not compelled to pass through the absorbent material, so that the saturation may be accomplished more quickly and with less pressure than where the fluid to

be saturated is compelled to pass through wicking or through a body of liquid.

In the operation of the device, the carbureting-chamber being partly filled with hydrocarbon, air is allowed to flow through an inlet 13 and traverse the tortuous passage formed by the several partitions 2, coming into contact with both sides of each piece of absorbent material 11 and finally escaping through a service-pipe 14, leading to the point of consumption.

For convenience in emptying the tank in case repairs are necessary or for the purpose of cleaning the tank an opening is formed in the cover, said opening being normally closed by a suitable cap 15. By removing this cap or block the suction-pipe of a pump may be introduced and the liquid contents of the tank removed.

Having thus described the invention, what is claimed is—

1. In a carbureter, a tank, a plurality of parallel partitions disposed therein and extending from the bottom to the top of the tank, said partitions being disposed in staggered relation, one end of each partition being connected to one side wall of the tank, and the other end being spaced from the opposite side wall of the tank, a plurality of open rectangular frames disposed in spaced relation in each of the spaces between each two partitions, said frames ex-

tending between the opposite side walls of the tank, and a layer of absorbent material carried on each side of the frames, forming between them distinct passages for the flow of air, the absorbent material terminating short of both ends of said frames.

2. The combination in a carbureter, of a shallow rectangular tank forming a closed compartment, vertical partitions arranged in staggered relation and extending from top to bottom of the tank, one of said partitions being shorter than the remainder, a pair of cross-bars serving as a support for the shorter partition and forming one of the boundaries of a compartment into which the hydrocarbon is admitted, the lower of said cross-bars serving further in connection with the remaining walls of the compartment to form a settling-chamber for the retention of deposits from the hydrocarbon, a valved inlet-pipe leading to such compartment, and a float disposed in the compartment and connected to the valve.

In testimony that we claim the foregoing as our own we have hereto affixed our signatures in the presence of two witnesses.

WALLACE L. SEVERANCE.
HENRY J. JOHNSON.
SAMUEL P. WALLACE.
